COMBINED COMPARTMENTED FOOD SERVING
TRAY AND INSERTS THEREFORStanford C. Stone, St. Paul, Minn., assignor to Plastics
Inc., St. Paul, Minn., a corporation of Delaware

Filed July 29, 1968, Ser. No. 12,939

Term of patent 14 years

Int. Cl. D7—01

U.S. Cl. D44—10

FIG. 5

FIG. 6

FIGURE 1 is a perspective view of a combined compartmented food serving tray and inserts therefor, showing my new design;

I claim:

The ornamental design for a combined compartmented food serving tray and inserts therefor, as shown.
